UNITED STATES PATENT OFFICE

EMIL CAHN, OF BERLIN-CHARLOTTENBURG, GERMANY

RAILROAD SLEEPER

Application filed November 11, 1929, Serial No. 406,459, and in Germany February 6, 1928.

The present invention relates to railroad sleepers and more particularly to hollow sleepers of iron of box cross-section. The invention consists of a sleeper having a 5 trough-shaped upper member or cover with side walls ending at their lower edges in outwardly turned flanges which engage rigidly in horizontal edges of a lower member which are hook-shaped in cross-section. The lower 10 member consists of a plate domed or of wave shape in the centre, and the side walls of the upper member slope slightly outwards from the vertical plane so that the hollow sleeper presents a spring effect when the load is 15 placed upon the top of the upper member. Both members may be made to the desired section by rolling, and the edges of the lower member may at first be made to stand upwards, and when the upper member is placed 20 in position, the edges may be turned over the flanges of the upper member again by a rolling process.

As a result of the invention, the lower member forms with the upper member a unitary 25 structure in which no relative movements can occur in contradistinction to the known construction of sleepers where relative movement gives rise to wear and weakening of the parts forming the joints between the 30 two members. The novel structure prevents broken stones and the like from penetrating into the flanges, and thereby prevents the formation of rust, weakening of the joint between the members, and, as already described, allows a certain resiliency or springing 35 of the sleeper. The two parts form a unitary sleeper structure of a resistance which remains constant and the spring action always remains the same.

40 Furthermore, the invention provides a secure support for the sleeper and also of the track because creeping of the sleeper and breaking up or grinding of the foundation support cannot occur as does happen in structures in which the upper member can move relatively to the lower member.

An embodiment of the invention is illustrated in the accompanying drawings, wherein:

50 Figure 1 shows a portion of a rail fixed

upon a sleeper, the latter being shown in cross-section to an enlarged scale;

Figure 2 is a longitudinal section showing part of the length of the sleeper; while

Figures 3 and 4 are longitudinal section 55 and plan respectively, showing the whole length of the sleeper.

The upper member 1 has substantially the shape of the usual railroad trough sleeper and is provided with horizontal external 60 flanges 2. The lower member 3 is domed or bulged upwardly at the centre and has horizontal hook-shaped extensions 4. The extensions 4 are first of all made to extend upwards and are later folded over the flanges 2 of the 65 upper member 1. In this way, the upper member 1 and the lower member 3 may be formed of two rolled sections. The two members may be joined together by folding over the extensions 4 which may also be effected by 70 a rolling process.

The method of fixing the rails does not form part of the invention. In the drawings a method of fixing by means of a welded-on ribbed plate 5, clamping chairs 6, and 75 hammer-headed bolts 7, is shown, illustrating the German Reichsbahn construction type K. Instead of this method of fixing the rails, however, any other suitable construction applicable for iron sleepers may be employed. 80

In action, the vertical limbs 8 of the upper member tend to spring outwards. They are prevented from doing so more or less by the lower member 3. They could only spring 85 outwards so far as is allowed by the yielding of the domed or bulged under-member 3. The construction, therefore, affords a spring action which provides a resistance when the limbs 8 spring apart, and when relieved of load, the limbs 8 return to the starting 90 position.

Owing to the domed or bulged section of the under-member 3 which is concave on its under surface, this member holds together the foundation material below the sleeper. Thus, the whole of the under surface of the 95 sleeper is continuously afforded a good support. Instead of the under surface being arc-shaped, it could be given a waved form.

The weight of a sleeper according to the 100

invention amounts to about 172 kilograms. This gives the sleeper a weight of 263.85 kilograms per meter run of the rails. The total weight of the rails and sleepers in the case of the German Reichsbahn construction type K amounts, for example, to 381.88 kilograms per meter run, and in the somewhat lighter Germany Government construction type B, for example, to 376.02 kilograms. The weight of the sleepers is thus relatively large in comparison with the total weight.

I claim:

1. A railroad sleeper, comprising a trough shaped upper member having outwardly inclined side walls the lower ends of which are outwardly extending horizontal flanges, and an upwardly domed lower member having hook shaped edges which rigidly engage the flanges of said upper member.
- 20 2. A device as in claim 1, in which the domed portion of the lower member limits the inward retraction of the upper member.
3. A railroad sleeper, comprising a trough shaped upper member having outwardly inclined side walls the lower ends of which are outwardly extending horizontal flanges, and an upwardly domed lower member extending along the entire length of the upper member and having hooked shaped edges which rigidly engage the flanges of the said upper member, the ends of the upper member being turned downwardly thereby to obstruct the openings at the ends of said device.

In witness whereof I hereunto subscribe my name this 24 day of October 1929.

EMIL CAHN.
